AUTO IGNITION LOCK

Filed May 19, 1928

FIG. 1 20°

UNITED STATES PATENT OFFICE

BURNETT B. HART AND BURCHARD L. HART, OF SAN DIEGO, CALIFORNIA

AUTO IGNITION LOCK

Application filed May 19, 1928. Serial No. 279,171.

My invention relates to automobile locks and more particularly to a lock for controlling the main battery circuit and the objects of my invention are: first, to provide a switch for positioning between the ungrounded terminal of a battery of a vehicle and the circuit supplied therefrom and a lock for preventing the operation of said switch by unauthorized persons; second, to provide means for preventing the engine from being turned by the electric starter and connection of the ignition coil or lights while the switch is locked in the open position; third, to provide a lock controlled switch for a vehicle which is inaccessible without the removal of certain parts of the lock and in which the cables leading to and from the switch are enclosed in metal conduits which cannot be removed or severed without considerable difficulty; fourth, to provide a switch of this description in which the terminals are positioned within the metal case and therefore inaccessible; fifth, to provide a switch contained within a case which is adapted to be secured on the rear side of an instrument board and cannot be removed therefrom without knowledge of the lock combination; sixth, to provide a switch with combination lock in which the lock knob and dial may be only withdrawn when the lock bolt is withdrawn from the switch operating means; seventh, to provide a lock controlled switch which may be readily mounted on the instrument board of any vehicle; and eighth, to provide a switch controlled lock of this description which is compact, economical of structure, simple, easy of manipulation and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is an elevational view of the combination lock and switch operating member

mounted on the front of the instrument board of a vehicle, a portion of the lock dial being broken away in order to show the concealed securing means; Fig. 2 is a sectional view taken along the line 2—2 of Fig. 1 showing certain portions in elevation; Fig. 3 is a sectional view taken along the line 3—3 of Fig. 2 showing certain portions in elevation and other portions broken away in order to facilitate the view of the illustration; Fig. 4 is a sectional view taken along the line 4—4 of Fig. 3, indicating in full and dotted lines the position assumed by the locking mechanism; and Fig. 5 is a sectional view taken along the line 5—5 of Fig. 3, showing the arrangement of the switch and lead connection therewith.

Similar characters of reference refer to similar parts and portions throughout the several views of the drawings.

The casing 1, combination lock mechanism 2, combination lock dial 3, combination lock stem 4, face plate 5, locking plate 6, switch operating knob 7, push and pull rod 8, knife switch 9, pivot terminal 10, contact clip 11, base 12, supports 13, brackets 14, conduits 15 and 16, and lock nuts 17 and 18, form the principal parts and portions of my vehicle lock.

The casing 1 is preferably made of sheet metal and is substantially of box shape in form, being open at its upper end. A conventional combination lock mechanism, such as the common Yale combination lock, is mounted within and at the forward portion of the casing 1. The lock casing, designated 2, is supported at the upper end of the casing 1 on suitable brackets 14 which may be made in L form, the one leg thereof being secured to the side of the casing, the other leg extending inwardly for supporting the combination lock 2 which is secured to said brackets by means of suitable screws 2a screwed into corresponding threaded holes in the bracket 14. The outer surface of the lock mechanism casing 2 is substantially flush with the edges of the casing 1. The length of the casing is sufficient to allow the bolt 2b of the lock mechanism to be extended to its normal locking position, as best shown in Fig. 2 of the drawings.

Rearwardly of the lock mechanism 2 I provide a switch mechanism including the base member 12 which may be mounted on supports 13 secured to the lock mechanism casing 2. A conventional knife blade switch 9 including the pivot member 10 and contact clip 11 are supported on the base 12 which is made preferably of insulating material. The free end of the knife blade 9 is provided with an operating lever member 9b loosely, 5 pivotally secured to the blade 9 by means of the pin 9a. The knife blade switch 9 is adapted to be opened and closed by means of the push and pull rod 8 which is secured at its one end to the lever member 9b and is 10 slidably supported in the bushing 5a which is secured to the face plate 5. The knob 7 is removably secured to the outer end of the rod 8 enabling the latter to be readily moved 15 backward and forward for operating the switch. The outer end of the bolt 2b is provided with a slot which enables the bolt to be slid over the reduced portion 8a of the pull rod 8, as clearly shown in Fig. 3. The 20 slot in the bolt 2b is adapted to register with the reduced portion 8a of the rod when the switch is in its open position, as shown in Fig. 2, so that it is impossible to withdraw the pull rod 8 when the bolt is in this position, thus preventing the switch blade 9 from 25 being brought into contact with the clip 11. The operation of the bolt 2b is of course carried out by the correct manipulation of the combination lock by means of the stem 35 4. The knob 4a is secured to the outer end of the stem 4 which extends through the lock mechanism casing and is adapted to be withdrawn from the lock mechanism. The dial 3 which is secured to the outer end of the 40 stem 4 and is rotatable therewith, is normally positioned in a suitable circular opening in the face plate 5. The casing 1 is secured by means of screws 2c entering the outer side of the clock mechanism casing 2, 45 to the instrument board B. These screws are normally concealed by the dial 3.

In order to remove the casing 1 from the instrument board B the knob 4a and dial 3 must therefore be withdrawn. In order to 50 prevent this being done by unauthorized persons, the stem 4 is provided at its inner end with a reduced portion 4b, the inner margin thereof being substantially flush with the rear surface of the lock mechanism casing 2. A bifurcated locking plate 6 is adapted 55 to be shifted into and out of engagement with the reduced portion 4b on operation of the bolt 2b. The outer end portions 6a of the bifurcated member are laterally offset and secured on either side of the slot in the outer 60 ends of the bolt 2b so that the bifurcated portions are adapted to straddle the rod 8 when the bolt 2b is extended. The free end of the locking plate 6 is adapted to slide in 65 between the laterally offset portion 13a of

the bracket 13 which acts as a guide, and the rear surface of the lock mechanism 2. Oppositely disposed shoulders are provided at the inner end of the locking plate arm 6a, the shoulders being spaced apart sufficiently to enable the reduced portion 4b of the stem 4 to be accommodated between them, when the locking plate 6 is shifted to its outer position by extending the bolt 2b. The shoulders 6b effectively prevent the stem 4a from being withdrawn, when the switch is locked in its open position. As clearly shown in Fig. 4 the push and pull rod 8 and stem 4a are both locked when the switch is open, the bolt 2b and locking plate 6 occupying the position shown in full lines in Fig. 4. When the bolt 2b is withdrawn the push and pull rod 8 and stem 4a are released, as indicated by the positions of the bolt and locking plate shown in dotted lines in Fig. 4.

In order to prevent tampering with the conductors leading to the switch terminals, the latter are preferably enclosed in the metal conduits 15 and 16, shown best in Fig. 5. The latter are secured to the casing 1 in any conventional manner, such as by means of the nuts 17 and 18 positioned on the inner side of the casing. The ends of the cable may be connected by conventional connectors C to the switch terminal, as shown best in Fig. 5. By extending the metal conduits over the length of the cable connected with the switch member and locking them to the casing in the manner described, it becomes practically impossible for an unauthorized person to short circuit the switch while any effort to remove the casing from the instrument board B is equally defeated by the inaccessibility of the screws securing the casing to the board.

It is obvious from the construction as illustrated in the drawings and described in the foregoing specification that there is provided a device as aimed at and set forth in the objects of the invention, and though I have shown and described a particular construction, combination and arrangement of parts and portions I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

1. In a device of the class described, a casing, a combination lock mechanism including bolt means supported therein, a normally operable switch supported in said casing, a normally removable stem for operating said lock mechanism and shifting said bolt means, a dial secured to and removable with said stem for concealing means for securing said casing to a vehicle instrument board, said bolt means being adapted to lock said switch

in inoperative position and lock said stem and dial against removal thereof from said lock mechanism.

2. In a device of the class described, a casing, a combination lock mechanism including a bolt supported within said casing, a switch supported within said casing, a push and pull rod connected to said switch for operating same, a reduced portion in said rod, a slot in said bolt adapted to register with said reduced portion and lock said rod in inoperative position, a normally removable stem for operating said combination lock and controlling said bolt, and locking means operable with said bolt adapted to prevent withdrawal of said stem when said rod is locked in inoperative position.

3. In a device of the class described, a casing, a combination lock mechanism, including a bolt supported within said casing, a switch supported within said casing, a push and pull rod connected to said switch for operating same, said rod extending substantially at right angles to said bolt, a reduced portion in said rod, a slot in the end of said bolt adapted to register with said reduced portion when the bolt is extended and the switch in open position, means for securing said casing to the rear of an instrument board, a normally removable stem for operating said combination lock, a dial secured to said stem and adapted to conceal said securing means, and a bifurcated locking plate secured to the outer end of said bolt and adapted to register with a reduced portion on said stem and prevent the withdrawal thereof when said bolt is extended.

4. In a device of the class described, an open ended metal switch casing, a combination lock casing secured to the open end of said casing, the outer surface of said lock casing being substantially flush with the edges of said switch casing, a switch positioned in the rear of said lock casing and within said switch casing, a push and pull rod extending from the switch to the open end of said switch casing for operating said switch, means for securing said switch casing to the rear of a vehicle instrument board, a face plate for positioning on the front of said instrument board, said plate having a bushing for slidably supporting said rod, a knob adapted to be secured to the outer end of said rod for operating same, a circular aperture in said plate, a removable lock operating stem including a dial adapted to register with said aperture and to conceal said casing securing means, and bolt means for locking said rod and preventing removal of said stem when said rod is locked.

In testimony whereof, we have hereunto set our hands at San Diego, California, this 11th day of May, 1928.

BURNETT B. HART.
